CLAIM

The ornamental design for a dust cap for fiber optical connectors as shown and described.

DESCRIPTION

FIG. 1 is a front perspective view of a dust cap for fiber optical connectors showing our design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a side view thereof;

FIG. 8 is an opposing side view thereof; and,

FIG. 9 is a perspective environmental view of the dust cap for fiber optical connectors secured to a fiber optical connector.

The broken lines are included for the purpose of illustrating portions of the dust cap for fiber optical connectors and form no part of the claimed design.
